FIG. 4

FIG. 3

INVENTOR

John V. Howey

By Harold D. Penney,

Attorney

UNITED STATES PATENT OFFICE.

JOHN VICTOR HOWEY, OF MUNSON, ALBERTA, CANADA.

PENCIL.

Application filed July 9, 1926, Serial No. 121,414, and in Canada January 28, 1925.

This invention relates to improvements in pencils appertaining particularly to that class of device having a barrel for containing a supply of leads.

5 An object is to provide such a device wherein a lead may be returned to its container, a new lead may be brought into use without handling, or a lead in use may be changed for one retained in supply.

10 A further object is to provide a device of this character having capacity for a number of marking elements of several colors or leads of various degrees of hardness.

15 A further object is to provide a pencil comprising a cylindrical body, a rotatable insert and a plunger held against rotation adapted to move longitudinally on the rotation of said insert.

20 A still further object is the provision of such a device wherein the parts are few, the construction simple and being capable of manufacture at a reasonable cost is thus rendered commercially desirable.

25 In the drawings, forming a part of this disclosure.

Fig. 1 is a plan of the pencil;

Fig. 2 is a longitudinal section;

20 Figs. 3 and 4 are transverse sections as on lines 3—3 and 4—4 respectively of Fig. 2; and

Fig. 5 is a detail elevation of the eraser applied to the top of the pencil.

In general the device approximates the conventional barrel type pencil but in detail includes novel features of construction providing for improved functions and increased uses and necessitating a change in the concealed operation. Comprising a cylindrical body within which both point and top ends are rotatable and frictionally retained, the pencil includes a fourth principal member in the form of a plunger with wings running in guides in the point end insert and held against rotation thereby and with an enlarged top threaded in the top insert is movable longitudinally in the barrel by the rotation of said top.

Referring particularly to the drawings, wherein like characters designate like parts throughout the several views, the numeral 6 designates the barrel like body having outwardly directed grooves or troughs 7 extending on the inner periphery from the point end 8 to from a third to a half way up the barrel.

A point end insert 9 is telescopically received by said barrel and frictionally though rotatably held therein. The exposed end 10 of this insert is enlarged, at the margin 11 abutting the barrel to the circumference 60 thereof but tapers to present a contour approximating the conventional pencil and the received stock 12 extends past the end of the grooves 7 for a purpose to be described later. A central perforation 13 extends longitudinally from the point of the tapered end 10, where the diameter is reduced as at 11, to the remote end of the stock and a slot 14 the full length of the stock is also provided. This slot provides communication for the perforation 13 with the exterior of the stock through the length thereof and leads or other markers 15 contained within the lead retaining grooves 7 may fall into the said perforation when the slot is brought 75 into registry with a lead containing and the pencil, held horizontally, is rotated till the groove, slot and perforation are vertically aligned with the former uppermost. The perforation is also provided with a pair of 80 diametrically opposite guide grooves 16 from the margin 11 to the end of the stock, the purpose of which will be later set forth.

The top end insert 17 is very similar to the point member 9 comprising a head 18 and a stock 19 the latter being of greater diameter than the stem 12 with which it abuts as it has no function in co-operation with the barrel except to be frictionally and rotatably retained thereby. This stock 19 85 is hollow and interiorly threaded to receive the enlarged and threaded head 20 of the plunger 21, the long slender stem 22 of which has near its remote end a pair of diametrically opposite wings 23 that slide in the 90 guides 16 of the stock 12. Thus it will be seen, that if the point end 9 is held against rotation and the top end insert 17 is turned the plunger whose rotation is restricted by the wings in guides 16, will move longitudinally.

When the plunger is retracted to the inner end of its threaded housing, the wings 23 will have reached the end of the guide grooves and be contacting with the abutting 105 end of the stock 19; and further that part of the plunger stem 22, exterior of the wings, will all be contained within that portion of the stock 12 that extends inwardly past the lead supply grooves 7, as aforesaid. Thus 110

it will be apparent that no obstacle is presented to the entry of a new lead or marking element.

In the head 20 an erasing element 24 is provided and mounted there between a pair of opposed standards 25 from the said head. The eraser is there retained by a transverse pin 26 passing through the eraser and standards. The whole is suitably enclosed by a container cap 27 screwed to the reduced threaded end 28 of the head 20.

In operation, the lead chamber or grooves 7 are filled and the device assembled; this is accomplished by reinserting the stock 12 in the barrel; the point and lead inserts are rotated with relation to each other till the wings 23 of the plunger stem locate their seats or guides 16; then, with the pencil horizontal and the perforation slot 14 extending downward from the axial perforation (this may be ascertained by the position of an arrow or other convention mark disposed on the exposed tapered end 10, that is in radial alignment with the said slot), the point insert is held while the barrel is rotated until the groove 7 containing the desired lead or marker registers with the slot when the whole pencil is rotated to bring the aligned groove, slot and axial perforation into vertical position with the former uppermost so the lead or other marker will fall into the perforation and then holding the point end against rotation, the head end is screwed to force the lead through the point and present it for use.

To exchange a lead or marker in use for one in supply, the plunger is retracted and the lead pressed back past the reduced and biting point 14 and returned to its chamber or groove by the reverse of the foregoing filling operation and the selected marker can then be brought into use as above.

From the foregoing description taken in connection with the accompanying drawings, it will be manifest that a pencil is provided which will fulfill all the necessary requirements of such a device, but as many changes could be made in the above description and many apparently widely different embodiments of my invention constructed within the scope of the appended claims without departing from the spirit or scope thereof,

it is intended that all matters contained in the said accompanying specification and drawings shall be interpreted as illustrative and not in a limited sense.

What I claim as new is:

1. In a pencil, a tubular body having a bore extending axially from end to end thereof, said bore having a shoulder intermediate its ends, the upper end of the bore being of larger diameter than the lower end, a rotatable internally threaded sleeve fitting in the upper end of the bore and bearing at its end against said shoulder, a head on said sleeve for rotating the same, a second sleeve removably and frictionally fitting in the lower end of said bore and having its lower end projecting from the bore and forming a shouldered point end with the shoulder bearing against the body end, said second sleeve having a slot extending longitudinally thereof, a plunger having its upper end enlarged and threaded to engage in the first sleeve and its lower end extending into the second sleeve, and a wing on said plunger engaging in said slot.

2. In a pencil, a tubular body having a bore extending axially from end to end thereof, said bore having a shoulder intermediate its ends, the upper end of the bore being of larger diameter than the lower end, a rotatable internally threaded sleeve fitting in the upper end of the bore and bearing at its end against said shoulder, a head on said sleeve for rotating the same, a second sleeve removably and frictionally fitting in the lower end of said bore and having its lower end projecting from the bore and forming a shouldered point end with the shoulder bearing against the body end, said second sleeve having a slot extending longitudinally thereof, a plunger having its upper end enlarged and threaded to engage in the first sleeve and its lower end extending into the second sleeve, and a wing on said plunger engaging in said slot in the said wall of the lower end of the bore, said slots forming lead holding recesses and the material between the slots forming ribs engaging and supporting the second sleeve axially of the body.

In testimony whereof I hereunto affix my signature.

JOHN VICTOR HOWEY.
